US00D946256S

(12) **United States Design Patent** (10) **Patent No.:** **US D946,256 S**
(45) **Date of Patent:** **** Mar. 22, 2022**

(54) **BOOT UPPER**

(71) Applicant: **Skechers U.S.A., Inc. II**, Manhattan Beach, CA (US)

(72) Inventor: **Yudiana Romero**, Los Angeles, CA (US)

(73) Assignee: **Skechers U.S.A., Inc. II**, Manhattan Beach, CA (US)

(**) Term: **15 Years**

(21) Appl. No.: **29/766,925**

(22) Filed: **Jan. 19, 2021**

(51) LOC (13) Cl. **02-04**

(52) U.S. Cl.

USPC **D2/970**; D2/911

(58) **Field of Classification Search**

USPC D2/896, 900, 909-911, 943, 946, 969,
D2/970, 974
CPC .. A43B 7/12; A43B 5/004; A43B 3/02; A43B
23/02

(57) **CLAIM**

The ornamental design for a boot upper, as shown and described.

DESCRIPTION

FIG. 1 is a front perspective view of an embodiment of the claimed design of the boot upper;

FIG. 2 is a rear perspective view thereof;

FIG. 3 is a side elevation view thereof;

FIG. 4 is an opposite side elevation view thereof;

FIG. 5 is a rear elevation view thereof;

FIG. 6 is a front elevation view thereof;

FIG. 7 is a top plan view thereof; and

FIG. 8 is a bottom plan view showing the claimed design of FIG. 1.

FIG. 9 is a front perspective view of a second embodiment of the claimed design of the boot upper in a folded down position;

FIG. 10 is a rear perspective view thereof;

FIG. 11 is a side elevation view thereof;

FIG. 12 is an opposite side elevation view thereof;

FIG. 13 is a rear elevation view thereof;

FIG. 14 is a front elevation view thereof;

FIG. 15 is a top plan view thereof; and,

FIG. 16 is a bottom plan view showing the claimed design of FIG. 9.

The broken lines shown in the drawings represent portions of the outsole that form no part of the claimed design.
